UNITED STATES PATENT OFFICE.

JULIUS FREDERIK GEORG POUL HARTMANN, OF COPENHAGEN, DENMARK.

ARRANGEMENT IN RECTIFIERS FOR ELECTRIC ALTERNATING CURRENTS.

1,322,187.

Specification of Letters Patent. Patented Nov. 18, 1919.

Application filed March 7, 1919. Serial No. 281,277.

To all whom it may concern:

Be it known that I, JULIUS FREDERIK GEORG POUL HARTMANN, a subject of the King of Denmark, residing at Copenhagen, Denmark, have invented new and useful Improvements in an Arrangement in Rectifiers for Electric Alternating Currents; and I do hereby declare the following to be a full, clear, and exact description of the same.

10 In a copending application Ser. No. 69,311 (now Patent 1,306,335) is indicated a rectifier for electric currents consisting of one or more conducting liquid jets, generally mercury jets, which pass through a 15 magnetic field perpendicular to the direction of the jet and strike an electrode. Through the interaction between current and field, waves are formed on the jet which move forward at the speed of the particles 20 of the jet, and the place at which the jet or the jets strike the electrode or electrodes sometimes divided by insulating partition walls, is thereby caused to move over the electrode in such a manner that the desired 25 rectification is effected.

In the said rectifiers the intensity of the rectified current is determinative of the height of the wave formed on the jet. Consequently the intensity of the rectified current must not decrease under a certain limit, as a regular rectification demands that the 30 wave should not become smaller than a certain size. In a rectifier with a plurality of jets it is possible to regulate the intensity of 35 the current downward from the maximal value by setting out of activity more or less jets; but where only one single jet is found, the regulation is rather limited.

A regulation of the intensity of the field, 40 whereby the same is augmented in relation to the decreasing of the intensity of current is rather difficult to effect automatically and is practically only possible within certain limits, as it is not possible to continually increase the intensity of field, which is essential 45 when the intensity of the current decreases toward zero, and the oscillation of the jet is to be kept up.

The invention relates to an improvement 50 in the said rectifiers making possible a regulation down to zero of the intensity of the rectified current.

According to the invention a current is conducted from a special auxiliary source of 55 current through the jet, which source of cur-

rent is inserted in a circuit arranged in parallel with the jet, the circuit further containing a commutator, which preferably consists of a conducting liquid jet of the same kind as the rectifying jet, which conducting liquid jet also passes a magnetic field and strikes an electrode, and such provisions have been made that this commutator establishes connection between the said circuit and the electrode or electrode- 60 parts of the rectifier during the period when this or these are touched by the rectifying jet, whereas it interrupts this connection during the period in which the electrode (or the part in question of the electrode) is not 65 touched by the rectifying jet. Thus there is always sufficient current flowing in the rectifier jet to keep it in motion, even if the current to be rectified becomes small or is cut off entirely. 70

Figure 1 shows diagrammatically a component part of a rectifier according to the invention;

Fig. 2 shows diagrammatically a complete rectifier for rectifying single phase alternating current, using a constant magnetic field and an auxiliary source of alternating current;

Fig. 3 shows diagrammatically a rectifier for single phase alternating current using an alternating magnetic field and a single auxiliary source of direct current;

Fig. 4 shows a similar modification but using two separate sources of auxiliary direct current;

Fig. 5 shows a modification of a rectifier using two rectifying jets, two corresponding constant magnetic fields and a single auxiliary source of direct current, and

Fig. 6 shows diagrammatically a rectifier for three phase alternating current using a revolving magnetic field and a single auxiliary source of direct current.

The broad principle of the invention appears from Fig. 1, which shows a component part of most of the above mentioned rectifiers. V designates the source of the alternating current, S designates the conducting rectifying jet, M a constant magnetic field the lines of force of which are 100 perpendicular to the plane of the paper, and E designates an electrode on one side limited by an insulating plate P, against the sharpened edge of which the jet is directed when in a currentless condition. In this 105 110

position the jet is in conductive connection with the electrode E, part of the jet running down along the oblique surface of the plate P. This apparatus is able to shut out 5 from the working conductor *a b* every other half period of the alternating current which the source of the alternating current would send through this wire if the jet remained unmoved in the position shown in the drawing. 10 ing.

As explained in the above named pending application the electrode E must be arranged at a distance from the field M equal to an odd multiple of the distance the parts 15 of the currentless jet would move during a half period of the alternating current. The apparatus will then act in such a manner that every other half period through interaction between the current and the magnetic field M produces a wave on the jet outward to the right so that the striking point of the jet is carried away from the electrode, and the conductor *a b* therefore is only 20 passed by the other half periods.

25 In order to keep up the motion of the parts of the jet necessary for the rectification, independently of the rectified current, a current of essentially the same nature as the rectified current flowing through the jet 30 during the rectification will have to be sent through the jet. In the case here under consideration there will thus have to be sent through the jet a pulsating current with the same number of periods as the current delivered by the source of alternating current 35 V and, what is of essential importance, in phase with the same. Such a current can be produced by a source of alternating current *v*, which is arranged in a branch circuit including the terminal *b*, jet S, and contact E. To connect the point *b* with the electrode E by means of a permanent closed wire would not in general be advisable, as in such case the source of alternating current 40 V would be short-circuited through this wire, and in the working conductor *a b* no rectified current would be obtainable. According to the invention therefore a kind of commutator or interrupter is used closing the connection during the period in 45 which the jet S touches the electrode E, but interrupts the connection between the electrode and the point *b* at the moment when the jet S leaves the electrode. Such a commutator is preferably made as a liquid jet 50 interrupter consisting of a liquid jet *s* flowing through a magnetic field *m* and striking an electrode *e* of the same kind as the electrode E. The electrode *e* can be adjusted toward and from the field *m* until the jet *s* strikes over the edge of the insulating plate *p* at the same moment that the jet *s* strikes over the edge of the plate P. It is understood that the pole tension for 55 the auxiliary source of current *v*, i. e., the

difference of potential between the points *c* and *d*, must be in phase with the pole tension of the source V of the alternating current, or the difference of potential between the points *a* and *f*. The distance of the electrode E from the field M is, as named, assumed to be an odd multiple of the distance through which the parts of the jet move during a half period of the alternating current, and the distance of the electrode 70 *e* from the field *m* must be fixed in a similar manner, which of course does not mean that the distances become alike, because the speed of the particles of the jets may differ, and another odd multiple may be chosen for the 75 distance passed by the particles of the jet during one half period. Practically the auxiliary apparatus consisting of the jet *s* and the appurtenant parts can be of lighter construction than the corresponding parts 80 of the rectifier proper as the auxiliary apparatus is to work with but the very small effect demanded by the maintaining of the oscillation of the jet S. In order to prevent the amplitude in a lighter jet from being 85 too great, the field *m* should simply be weakened. With the same speed for the particles of the jets S and *s* the intensity of the field *m* should normally be made as many times smaller than that of the field 90 M as the cross section of the jet S is greater than that of the jet *s*. It may be remarked that the field *m* must have a direction opposite to that of the field M, because the current in the jet *s* is flowing in a direction 95 opposite to that of the current in the jet S.

100 It will now be shown how the above explained principle can be used for the various practical modifications for rectifiers of the kind in question.

105 In the modification shown in Fig. 2 the jet S is to convey alternating current which is delivered by the source of current V. The jet passes a constant field M and strikes a double electrode, the parts *E*₁ and *E*₂ of 110 which are separated by means of an insulating plate. An auxiliary system is provided which has a jet *s*, similar to the jet S, one terminal of which is so connected to source of current V that a portion *v* thereof furnishes sufficient current for the auxiliary system. The jet *s* strikes an electrode, the parts *e*₁ and *e*₂ of which are connected with the parts *E*₁ and *E*₂, respectively, as shown. The field *m* is a constant field. The distance from the electrode *e*₁, *e*₂ from the field *m* is adjusted in such a manner that the striking point of the jet *s* passes over from the electrode *e*, to the electrode *e*₂ at the same time that the jet S passes from 115 the electrode E, to the electrode *E*₂, and vice versa. In this modification the working circuit or resistance is divided, each of the two directions of current flowing through its 120 working resistance *R*₁ and *R*₂ respectively. 125

It appears from the above that the current in the jet S due to the source V of alternating current will be superposed over the current through the jet s from the source v of 5 alternating current and thereby augment the amplitude of the oscillation of the jet S. As long as the rectified current is kept below a certain limit, however, it will not be necessary on this account to regulate 10 the intensity of the auxiliary current, as even very considerable variations in the amplitude of the rectifying jet are allowable.

In Fig. 3 is shown a system with an undivided working circuit or resistance R, 15 while the source of alternating current consists of two halves V_1 and V_2 . The field M is here an alternating field fed with current from the same generator which delivers the current to be rectified. Through the jet 20 S flows in this modification the rectified current proper which has the character of an unbroken direct current. The auxiliary current which is sent through the jet s will then have to be a direct current also. This 25 latter is appropriately taken from a storage cell B. The alternating field m is fed with the same current as the alternating field M, which current is appropriately delivered by the source of current V_1 , V_2 as indicated in 30 the drawing. The system containing the jet S is presumed to be adjusted for normal rectifying. The distance of the electrodes e_1 , e_2 from the field m is adjusted in such a manner that the striking point of the jet s passes 35 over from the electrode e_1 to the electrode e_2 , at the same moment that the jet F passes over from the electrode e_1 to the electrode E_2 . Instead of, as shown, arranging the storage cell B between the points g and h, the 40 same may be inserted between the points g and k. Finally a storage cell B_1 and B_2 may be inserted in each of the two wires n_1 and n_2 , which connect the electrode parts in question, as shown in Fig. 4, which represents a similar 45 rectifier.

In Fig. 5 is shown a rectifier composed of two systems similar to that shown in Fig. 1. The working conductor a b is here undivided, and during the rectifying direct 50 current is constantly flowing through the same. The pulsating currents which are here to be produced in the two jets S_1 and S_2 , may be taken from a storage cell B, which, as shown, is inserted in a circuit containing the auxiliary jet s common for the 55 two jets S_1 and S_2 , and the system which effects the maintaining of the connection in this manner between the source B of auxiliary current and the jets S_1 and S_2 may be of 60 the kind shown in Fig. 3. The winding for the magnet producing the magnetic field m is fed with current from the same generator which delivers the current to be rectified. It is understood that it will be possible to 65 find one or more positions of the electrode

e_1 , e_2 in which the striking point of the jet s passes over from the part e_1 to the part e_2 contemporaneously with the jet S_1 leaving the part E_1 and the jet S_2 entering the part E_2 . The pulsating current which in this apparatus flows from the source of current B through the jets S_1 and S_2 will not have the same shape of curve as that delivered by the source of current V_1 , V_2 , but it will have the same frequency and be in phase with 70 the same, which is all that is demanded for maintaining the necessary motion of the jets S_1 and S_2 , also when the intensity of the rectified current decreases to zero or to a low value. 75

Finally Fig. 6 shows diagrammatically a rectifier with rotating field for cases where the number of the phases is three. The windings of the generator are designated by V_1 , V_2 and V_3 . The coils producing the rotating field actuating the jet S are designated by M_1 , M_2 and M_3 , and the parts of the electrodes by E_1 , E_2 , and E_3 . The auxiliary system consists of a jet s passing 80 a rotating field produced by the coils m_1 , m_2 and m_3 , and striking an electrode consisting of the mutually insulated sectors e_1 , e_2 and e_3 . The various parts are connected by wires as indicated. During 85 the rectification, in the jet S flows a direct current, and the auxiliary current is appropriately taken from a storage cell B inserted between the two jets S and s, which in the figure are represented as points. The field coils m_1 , m_2 and m_3 are preferably inserted in series with the coils M_1 , M_2 and M_3 , 90 respectively, as indicated. 95

The auxiliary system not only enables regulation of the rectified current down to zero but makes possible the rectification of relatively high tension current by relatively small intensities of current. In the system shown in Fig. 3 and in multiphase systems with rotating field the auxiliary system may be used as starting means, and it does away 100 with the drawback otherwise attached to the said kinds of rectifiers that the direction of the rectified current is a matter of chance. When the rectifiers are started by means of auxiliary systems, the rectified current 105 in the jet will always get the same direction as the auxiliary current. 110

Having thus fully described my invention, I claim as new and desire to secure by Letters Patent—

1. The combination of a liquid jet rectifier for alternating currents comprising a conducting jet, and means for keeping said jet in motion during all variations in the strength of the rectified current, including 125 an auxiliary circuit shunted across the jet.

2. The combination of a liquid jet rectifier for alternating currents comprising a conducting jet, and means for keeping said jet in motion during all variations in the 130

strength of the rectified current, including an auxiliary circuit and conducting jet shunted across the first named jet.

3. The combination of a liquid jet rectifier for alternating currents comprising a conducting jet and a plurality of electrodes normally impinged upon by said jet when no rectified current is passing, and means for keeping said jet in motion during all 10 variations in the strength of the rectified current, said means including an auxiliary circuit shunted across the jet and electrodes.

4. The combination of a liquid jet rectifier for alternating currents comprising a conducting jet, and means for keeping said jet in motion during all variations in the strength of the rectified current, including an auxiliary circuit and conducting jet shunted across the first named jet, and means 15 for causing said auxiliary jet to move in synchronism with the rectifier jet.

5. The combination of a liquid jet rectifier for alternating currents comprising a conducting jet and a plurality of electrodes normally impinged upon by said jet when no rectified current is passing, and means for keeping said jet in motion during all 20 variations in the strength of the rectified current, said means including an auxiliary

circuit shunted across the jet and electrodes, 30 and means for causing said auxiliary jet to move in synchronism with the rectifier jet.

6. A rectifier for electric alternating currents, comprising a conducting liquid jet, 35 means for producing a magnetic field crossed by the said jet, and means comprising an electrode for passing an electric current through the said jet, the said field and current being of such a character as to produce a 40 periodical force acting on the said jet, a circuit comprising an auxiliary source of current a commutator consisting of an auxiliary liquid jet, means for producing a magnetic field coacting with the said auxiliary jet to produce oscillations of the same, and an auxiliary electrode connected with the first named electrode, the said commutator being adapted to automatically establish connection between the said circuit 45 and the first named electrode during the periods in which the same is touched by the said jet, and to interrupt the said connection during the periods in which the said electrode is not touched by the said jet. 50

In testimony whereof I have affixed my signature.

JULIUS FREDERIK GEORG POUL HARTMANN. 55
